UNITED STATES PATENT OFFICE.

JOHN HENRY HINDLE AND THOMAS HINDLE, OF HASLINGDEN, ENGLAND.

LOOM FOR WEAVING.

Application filed September 30, 1925, Serial No. 59,736, and in Great Britain December 17, 1924.

This invention relates to looms more particularly to wide looms for weaving heavy wide fabrics.

In such looms, which may be up to over 250 inches in width, the slay beam and the crank shaft are subjected to heavy stress due to beating up the weft and pulling forward the warp at each pick. If not sufficiently stayed serious deflection of the slay beam takes place, causing the weft to assume a curved structure instead of a straight line across the piece.

According to the invention the slay is supported on one, two or more intermediate slay swords of such construction as not to interfere with the healds or warps; and the crank shaft which is provided with one, two or more intermediate cranks one for each intermediate slay sword is supported by bearings, one on each side of each crank fitted to intermediate frames attached to both the front beam and the back beam of the loom so that the thrust in beating up is sustained by the back beam and is to a large extent counter-acted or taken up by the warps placing the frame members in compression, a knocking off dagger and lever being fitted to each intermediate slay sword.

The invention will be fully described with reference to the accompanying drawings.

Fig. 1 is a transverse sectional elevation on line 1—1 Fig. 3 showing more particularly one of the intermediate slay swords D², one of the intermediate cranks F² and one of the intermediate frames A¹.

Fig. 2 is a transverse sectional elevation showing more particularly one of the end frames A, one of the end slay swords D¹ and one of the end cranks F¹.

Fig. 3 is a plan showing more particularly the back beam H the breast beam K one end frame A, intermediate frames A¹ and cranks F² driving shaft G and gears g.

Fig. 4 is a longitudinal sectional elevation.

The loom is constructed with a rigid framing comprising two end frames or gables A which bear the weight of the structure, two longitudinal beams or girders B extending the length of the loom and affixed to the gables A and a number of transverse rails or beams C between the two longitudinal girders B which form supports for the intermediate working parts of the loom.

Intermediate of the end frames or gables A one, two or more sets (according to the

length of the loom) of intermediate brackets or frames A¹ are fitted transversely being mounted upon the transverse rails C and secured to the longitudinal girders B. The intermediate frames are fitted in pairs to give support more particularly to the cranks and crank shaft.

The slay D and reed d are of ordinary construction for this type of loom carried by a slay sword D¹ at or near each end to which both the slay sole and slay cap are attached. To the slay are also fitted one, two or more slay swords D² intermediate of the slay swords D¹ to give additional support to the slay when beating up. These additional and intermediate slay swords D² are of such a shape or construction as to attach to the slay sole or beam only without projecting above it and to allow free space for the healds and warp yarn which will pass over the top of them.

The slay swords D¹ and intermediate slay swords D² are mounted loosely on shafts E supported in bearing brackets e screwed or bolted to the transverse rails or beams C preferably one to each rail on each side of the sword to give rigidity to the shaft E.

The slay swords D¹ are fitted with crank connecting arms d¹ and each of the intermediate slay swords D² is fitted with a crank connecting arm d² to connect with a corresponding crank so that all the slay swords are simultaneously operated together during the beat up of the loom to equalize the pressure upon the slay throughout its length and prevent deflection or bending towards the centre.

The crank shaft F is constructed with the ordinary end cranks F¹ and with one, two or more intermediate cranks F² corresponding to the number of intermediate slay swords D². The crank shaft F is supported in bearings f on the end gables A and also in a number of bearings f² on the intermediate frames A¹ each crank being supported on two sides to give rigidity thereto.

The crank shaft F instead of being driven from the end is driven from an auxiliary driving shaft G which conveys the power across the loom by gears g at two or more points throughout its length to reduce torsional deflection in the length of the crank shaft. The driving shaft G is carried in bearings g¹ on the intermediate frames A¹ adjacent to the gears g.

The back beam H and the breast beam K

are attached to the end gables A in the usual way and are also affixed to the upper ends of the intermediate frames or bearing brackets A¹ which are bolted to the cross rails C and longitudinal girders B.

The intermediate frames A¹ also carry bearings m for the tappet shaft M which is situated below the crank shaft F, and tension rods or bars N for the warps.

10 The warps pass from beams or creels (not shown) over the tension rods or bars N the back beam H and across the loom over the breast beam to the taking up motion and by this construction the warps being held in 15 tension by the back beam H between it and the breast beam K the force of the beating up of the weft places the intermediate frames in compression thereby greatly reducing the strain upon the fixed parts of the loom.

20 The shedding is effected from tappet or cams on the shaft M.

The warp protector or knocking off motion may be similar to that of a fast reed loom through daggers O attached to each of the 25 swords D¹ and intermediate swords D² and a corresponding number of dagger levers O¹.

The take-up motion is described and claimed in our Patent #1,630,428, dated May 31, 1927, and comprises two plain rollers, P, 30 P¹ geared together to rotate in the same direction, and an idle roller pressing against the other two the cloth being passed over the front beam round the two rollers with a loop round the idle roller and thence to a lap 35 roller upon which it is wound, the tension holding the idle roller tightly against the periphery of the other two and preventing a backward movement of the cloth.

40 By this construction undue stresses in the loom are eliminated, deflection of the slay beam and reed avoided and a much better cloth is produced.

What we claim as our invention and desire to protect by Letters Patent is:—

45 1. In a loom constructed with a slay and end swords attached thereto, breast and back

beams and a plurality of intermediate slay swords attached to the slay the combination of a plurality of transverse intermediate frames mounted in pairs to support the parts 50 of the loom spanning the front and back beams, one frame being adjacent to each side of each intermediate slay sword, a crank shaft positioned well up in the loom immediately below the warp threads, a plurality 55 of intermediate cranks on the crank shaft to push the slay swords from the back beam simultaneously so that the thrust in beating up is sustained by the back beam placing the intermediate frames in compression and a plurality of bearings in pairs supported by the transverse frames one bearing being on 60 each side of each crank to support the crank shaft, gears to drive the crank shaft and a knocking off dagger and lever for each intermediate slay sword.

2. A loom for weaving comprising in its construction, breast and back beams and two end gable frames, two longitudinal girders attached thereto extending the length of the 70 loom, a plurality of transverse beams bolted to the longitudinal girders, a plurality of pairs of intermediate transverse frames affixed to the breast and back beams, end slay swords and a slay mounted on the slay 75 swords, a plurality of intermediate slay swords each pivoted between a pair of the intermediate transverse frames and also attached to the slay to place the breast and back beams and intermediate frames in compression and a crank shaft, a plurality of cranks mounted thereon, bearings for the crank shaft in each intermediate frame between which the intermediate slay swords oscillate, a driving shaft and gears to operate 80 the slay swords and a knocking off dagger and lever for each intermediate slay sword.

In testimony whereof we have hereunto set our hands.

JOHN HENRY HINDLE.
THOMAS HINDLE.
